US0D1078536S

(12) **United States Design Patent** (10) **Patent No.:** **US D1,078,536 S**
(45) **Date of Patent:** **** Jun. 10, 2025**

(54) **PLANT PROPAGATION STATION**

(71) Applicant: **Menghua Li**, Guangdong (CN)

(72) Inventor: **Menghua Li**, Guangdong (CN)

(**) Term: **15 Years**

(21) Appl. No.: **29/981,950**

(22) Filed: **Jan. 3, 2025**

(51) **LOC (15) Cl.** **11-02**

(52) **U.S. Cl.**

USPC **D11/149**; D11/143; D11/146

(58) **Field of Classification Search**

(57) **CLAIM**

The ornamental design for a plant propagation station as shown and described.

DESCRIPTION

FIG. 1 is a top perspective view of a plant propagation station showing my new design;

FIG. 2 is another top perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof; and,

FIG. 9 is a bottom perspective view thereof.

The broken line and lightened portions shown within the broken line illustrate portions of the plant propagation station that forms no part of the claimed design.

1 Claim, 9 Drawing Sheets
